United States Patent

Des. 235,398
Patented June 17, 1975

235,398

RECESSED TISSUE HOLDER

Raymond U. H. Tegner, Lodi, Wis., assignor to
Amerock Corporation, Rockford, Ill.

Filed Dec. 26, 1973, Ser. No. 427,839

Term of patent 14 years

Int. Cl. D6—06

U.S. Cl. D6—97

fig. 2.

FIG. 1 is a front view of a recessed tissue holder incorporating my new design.

FIG. 2 is a bottom view of the tissue holder.

FIG. 3 is a side view of the tissue holder as seen from the right of FIG. 1.

FIG. 4 is a sectional view taken along the line 4—4 in FIG. 1.

FIG. 5 is a fragmentary sectional view taken along the line 5—5 in FIG. 1.

FIG. 6 is a fragmentary sectional view taken along the line 6—6 in FIG. 1.

I claim:

The ornamental design for a recessed tissue holder, as shown.
